UNITED STATES PATENT OFFICE.

PETER A. LAWLESS, OF NEW YORK, N. Y.

PASTING MECHANISM.

SPECIFICATION forming part of Letters Patent No. 780,004, dated January 10, 1905.

Original application filed April 20, 1903, Serial No. 153,483. Divided and this application filed September 7, 1904. Serial No. 223,594.

To all whom it may concern:

Be it known that I, PETER A. LAWLESS, a citizen of the United States, residing at New York city, county of New York, and State of New York, have invented certain new and useful Improvements in Pasting Mechanisms, fully described and represented in the following specification and the accompanying drawings, forming a part of the same.

This invention relates to mechanism for applying a line of paste or other adhesive material to paper or other material, and this application is a division of an application filed by me on the 20th day of April, 1903, Serial No. 153,483.

The invention has been made especially with the idea of providing suitable pasting means for use with a cigarette-machine of that class in which a continuous wrapper-strip is folded about a continuous rod of tobacco and the edges of the wrapper-strip pasted together to form a continuous cigarette-rod, and the invention aims to provide a device which shall be simple and easy of adjustment and especially adapted to apply a thin even line of paste to the edge of the wrapper-strip. Although the device is intended especially for use with a continuous-rod-cigarette machine, it will be understood that it is not to be limited to such use.

A full understanding of the invention can best be given by a detailed description of a preferred construction embodying the various features thereof, and such a description will now be given in connection with the accompanying drawings.

In said drawings, Figure 1 is a plan view of a pasting mechanism constructed in accordance with the invention and of the filler forming and wrapping mechanism of the cigarette-machine of my original application, Serial No. 153,483. Fig. 2 is a view looking in the direction of the arrow 2 of Fig. 1. Fig. 3 is a section on line 3 of Fig. 1. Fig. 4 is a view looking in the direction of the arrow 4 of Fig. 1.

In the preferred construction shown in the drawings a horizontally-rotating pasting-disk

60 takes paste from a vertically-rotating roll 61, mounted in a suitable paste-receptacle, as 50 62, and coöperating with a grinding-roll 63, which in turn coöperates with another grinding-roll 64, the two rolls 63 and 64 rotating downwardly toward and from each other, as indicated by arrows on Fig. 3, and the roll 61 55 rotating upwardly toward and from the roll 63. The roll 61 has a concave or circumferentially-grooved periphery to conform to the periphery of the pasting-disk 60, and the roll 63 is formed with a convex periphery corresponding to the grooved roll 61, and the roll 64 has a concave periphery to correspond with the convex periphery of the roll 63. The rolls 63 and 64 are preferably roughened to secure a better grinding action. A doctor-blade 65 60 is provided for the roll 61 and is formed with a central notch 66 (shown in Fig. 3 and in dotted lines in Fig. 4) for causing a circumferential line of paste to be carried by the roll 61 to the pasting-disk 60. This doctor-blade 70 65 is preferably adjustable, as by being pivotally supported, as shown, and adjusted by means of a screw 67. The edge of the pasting-disk 60 is preferably beveled upward, as shown.

While it may not in all cases be necessary to provide the grinding-roll 64, yet the arrangement shown having the two grinding-rolls 63 and 64 in addition to the roll 61 is preferred and forms a feature of the invention. With this construction and with the rolls mounted to rotate vertically and the rolls 63 and 64 preferably rotating downwardly toward and from each other, a very thorough grinding of the paste is secured and all necessity of grinding the paste before placing it in the paste-receptacle is avoided. This pasting apparatus is especially designed for use with a continuous-rod-cigarette machine and is shown as associated with the wrapping-tube 90 of such a machine for applying a line of paste to the edge of the wrapper-strip as the latter is advanced through the wrapping-tube. The wrapping-tube shown is the tube described and claimed in my said original application, 95 Serial No. 153,483, comprising a rod or bar

25, having a longitudinal groove 26 and guides for turning the two side edges of the wrapper-strip *x* successively inward and down to overlap on the tobacco to form the continuous cigarette-rod, and the paste is applied to the last folded side of the wrapper-strip as it passes the pasting-guide 46.

It is desirable to provide means for accurately adjusting the pasting-disk 60 with relation to the wrapping-tube and the edge of the wrapper-strip, and also to provide for relative adjustment between the pasting-disk and the paste-roll 61. The construction shown provides well for such adjustment. As shown, 15 the paste-fountain 62 and the pasting-disk 60 are carried by a bracket 70, the paste-fountain being secured to a slide 71, mounted on the bracket 70 and adjustable thereon toward and away from the pasting-disk, as by means of a screw 72. The pasting-disk is carried by a spindle mounted in screw-bearings 73 and 74, which may be adjusted to elevate or lower the pasting-disk with relation to the paste-roll 61. The bracket 70 is carried by a slide 25 75, supported by a bracket 76 and adjustable thereon, as by a screw 77, to move the pasting apparatus to carry the pasting-disk 60 toward or away from the wrapping-tube and the edge of the wrapping-strip, and the bracket 30 70 is pivotally mounted at its outer end and may be swung upward or downward to raise or lower the pasting-disk with relation to the wrapping-tube and the edge of the wrapping-strip by means of an adjusting-screw 78 acting against the tension of a spring 79. The paste-fountain 62 is preferably removably secured to the slide 71, as by being held at one end by means of an undercut flange 80 and at the other end by means of side holding-screws 81. By loosening the screws the fountain may thus be readily removed from the slide 71.

Any suitable means may be provided for driving the pasting-disk and the paste feeding and grinding rolls. As shown, the pasting-disk is driven from a shaft 136 by means of a belt 137, running on pulleys on the shaft 136 and on the shaft of the pasting-disk, respectively, and the shafts of the rolls 61, 63, 50 and 64 carry intermeshing gears 140 and are driven by means of a belt running on a pulley on the shaft of the roll 64.

It will be understood that the invention is not to be limited to the exact construction and arrangement of parts as shown for the purpose of illustrating the invention, and to which the foregoing description is mainly confined, but that the invention includes changes and modifications thereof within the claims.

60. What is claimed is—

1. The combination of a paste-feeding roll having a longitudinally-concave periphery, a doctor having a notch for securing a circumferential line of paste on said roll, and a past-

ing-disk rotating in a plane transverse to the plane of rotation of said roll and mounted to take paste from said roll, substantially as described.

2. The combination of a paste-feeding roll having a longitudinally-concave periphery, a doctor having a notch for securing a circumferential line of paste on said roll, a pasting-disk rotating in a plane transverse to the plane of rotation of said roll and mounted to take paste from said roll, and a grinding-roll for 75 coating with said paste-roll, substantially as described.

3. The combination of a paste-receptacle, a plurality of vertically-rotating grinding-rolls mounted in said receptacle, a vertically-rotating paste-feeding roll for receiving paste from and coating with one of said grinding-rolls, and a pasting-disk rotating in a plane transverse to the plane of rotation of said paste-feeding roll and mounted to take paste therefrom, substantially as described. 80

4. The combination of a paste-receptacle, a pair of vertically-rotating grinding-rolls mounted in said receptacle and rotating downwardly toward and from each other, and a vertically-rotating paste-feeding roll mounted to receive ground paste from and to coat with one of said grinding-rolls, substantially as described. 90

5. The combination of a paste-receptacle, a pair of vertically-rotating grinding-rolls mounted in said receptacle and rotating downwardly toward and from each other, one of said rolls having a longitudinally-convex periphery and the other of said rolls having a longitudinally-concave periphery, a vertically-rotating paste-feeding roll having a longitudinally-concave periphery receiving paste from and coating with the convex grinding-roll, and a pasting-disk rotating in a plane 105 transverse to the plane of rotation of said feeding-roll and mounted to take paste therefrom, substantially as described. 100

6. The combination of a paste-receptacle, a paste-feeding roll having a longitudinally-concave periphery, a doctor having a notch for securing a circumferential line of paste on said roll, a pasting-disk rotating in a plane transverse to the plane of rotation of said roll and mounted to take paste therefrom, a grinding-roll having a longitudinally-convex periphery coating with said paste-roll, and a second grinding-roll having a longitudinally-concave periphery coating with the first said grinding-roll, substantially as described. 110 115

7. The combination of a paste-receptacle, a paste-feeding roll having a longitudinally-concave periphery, a pasting-disk rotating in a plane transverse to the plane of rotation of said roll and mounted to take paste therefrom, a grinding-roll having a longitudinally-convex periphery coating with said paste-roll, and a second grinding-roll having a longitudinally-concave periphery coating with the first said grinding-roll, substantially as described. 120 125

gitudinally-concave periphery coacting with the first grinding - roll, substantially as described.

8. The combination of a paste-feeding roll, 5 a pasting-disk rotating in a plane transverse to the plane of rotation of said roll and taking paste therefrom, means for adjusting one of said members relatively to the other in a direction substantially parallel with the axis 10 of the pasting-disk, and means for adjusting one of said members toward and from the other and transversely to the axis of the pasting-disk, substantially as described.

9. The combination with the wrapping devices of a continuous-rod cigarette machine, of 15 a pasting device comprising a pasting-disk for applying a line of paste to one edge of the wrapper-strip, a paste-roll rotating in a plane transverse to the plane of rotation of said disk 20 and mounted to supply paste thereto, means for adjusting said pasting-disk longitudinally of its axis with relation to the paste - roll, means for adjusting one of said members of

the pasting device toward or from the other, and means for moving said pasting device 25 bodily to adjust the position of the pasting-disk with relation to the edge of the wrapper-strip, substantially as described.

10. The combination of the paste-receptacle 62, paste-roll 61 carried thereby, pasting-disk 30 60 rotating in a plane transverse to the plane of rotation of the roll 61, bracket 70 on which said parts are mounted, means for adjusting the paste-receptacle on the bracket 70 toward and away from the pasting-disk 60, means for 35 adjusting the pasting-disk 60 longitudinally of its axis, and means for adjusting the position of the bracket 70, substantially as described.

In testimony whereof I have hereunto set my hand in the presence of two subscribing 40 witnesses.

Correction in Letters Patent No. 780,004.

It is hereby certified that Letters Patent No. 780,004, granted January 10, 1905, upon the application of Peter A. Lawless, of New York, N. Y., for an improvement in "Pasting Mechanism," was erroneously issued to said "Lawless" as owner of said invention; whereas the said Letters Patent should have been issued to *The American Tobacco Company, New York, N. Y.*, a corporation of New Jersey, as owner of the entire interest in said invention, as shown by the assignments of record in this office; and that the said Letters Patent should be read with this correction therein that the same may conform to the record of the case in the Patent Office.

Signed and sealed this 21st day of February, A. D., 1905.

gitudinally-concave periphery coacting with the first grinding - roll, substantially as described.

8. The combination of a paste-feeding roll, 5 a pasting-disk rotating in a plane transverse to the plane of rotation of said roll and taking paste therefrom, means for adjusting one of said members relatively to the other in a direction substantially parallel with the axis 10 of the pasting-disk, and means for adjusting one of said members toward and from the other and transversely to the axis of the pasting-disk, substantially as described.

9. The combination with the wrapping devices of a continuous-rod cigarette machine, of 15 a pasting device comprising a pasting-disk for applying a line of paste to one edge of the wrapper-strip, a paste-roll rotating in a plane transverse to the plane of rotation of said disk 20 and mounted to supply paste thereto, means for adjusting said pasting-disk longitudinally of its axis with relation to the paste - roll, means for adjusting one of said members of

the pasting device toward or from the other, and means for moving said pasting device 25 bodily to adjust the position of the pasting-disk with relation to the edge of the wrapper-strip, substantially as described.

10. The combination of the paste-receptacle 62, paste-roll 61 carried thereby, pasting-disk 30 60 rotating in a plane transverse to the plane of rotation of the roll 61, bracket 70 on which said parts are mounted, means for adjusting the paste-receptacle on the bracket 70 toward and away from the pasting-disk 60, means for 35 adjusting the pasting-disk 60 longitudinally of its axis, and means for adjusting the position of the bracket 70, substantially as described.

In testimony whereof I have hereunto set my hand in the presence of two subscribing 40 witnesses.
